(57) **CLAIM**

The ornamental design for a book cabinet, as shown and described.

DESCRIPTION

FIG. 1 is a front perspective view of a book cabinet showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view thereof with the door being opened;

FIG. 9 is an enlarged view of portion 9 in FIG. 1; and,

FIG. 10 is an enlarged view of portion 10 in FIG. 8.

The evenly broken lines in the drawings illustrate portions of the book cabinet that form no part of the claimed design. The dash-dot-dash broken lines in FIGS. 1, 8, 9, and 10 illustrate the border of the enlarged views and form no part of the claimed design.

1 Claim, 10 Drawing Sheets
